UNITED STATES PATENT OFFICE.

ARTHUR B. DAVENPORT, JR., OF PHILADELPHIA, PENNSYLVANIA, AS-SIGNOR TO WILLIAM WHARTON, JR., & COMPANY, INCORPORATED, OF SAME PLACE.

CASTING-CLAMP FOR TRACK STRUCTURES.

SPECIFICATION forming part of Letters Patent No. 678,166, dated July 9, 1901.

Application filed January 24, 1900. Serial No. 2,632. (No model.)

To all whom it may concern:

Be it known that I, ARTHUR B. DAVENPORT, Jr., a citizen of the United States, residing in Philadelphia, Pennsylvania, have invented 5 certain Improvements in Casting-Clamps for Track Structures, of which the following is a specification.

The object of my invention is to provide means whereby rails or other similar structures can be readily secured in proper position and held there during the process of uniting them rigidly together by cast metal. This object I attain in the following manner, reference being had to the accompanying 15 drawings, in which—

Figure 1 is a plan view of my improved clamp for holding the rails in place during casting. The view illustrates the rail-sections of a frog in position. Fig. 2 is a side view of 20 Fig. 1. Fig. 3 is a sectional view on the line 3 3, Fig. 1. Fig. 4 is a plan view of the base-plate. Figs. 5 and 6 are views of the supporting-blocks used in connection with the base-plate. Fig. 7 is a plan view of the sup- 25 porting-plate, slightly differing in form from that shown in Fig. 1 and used for long and narrow structures, such as switches and switch mates. Fig. 8 is a side view of Fig. 7; and Fig. 9 is a sectional view on the line 30 9 9, Fig. 7.

Referring in the first instance to Figs. 1 to 6, inclusive, A is a base-plate, and in the upper face of this plate are a series of grooves a a' a'', which cross at the center, as shown in 35 Fig. 2. These grooves extend the full length of the plate in the present instance, and mounted on the plate A are blocks B, having tongues b, which fit snugly in the grooves. These blocks can be adjusted within the 40 grooves in any position from and toward the center of the plate and are for the purpose of keeping the main rail-sections in alinement and sufficiently far from the base-plate to allow for the proper ramming of the sand of 45 the mold. It will be observed that the grooves which act as guides for the blocks each have their parts in alinement—that is to say, each groove so extends that when the blocks are mounted therein said blocks are 50 held in a proper alinement corresponding to

the alinement required for the rail-sections which are supported upon said blocks. The grooves form longitudinal guides to hold the blocks having tongues in alinement. On the upper face of each block B is a rib b', prefer- 55 ably of the contour of the groove of the main rail-sections C C', Fig. 1. In the present instance there are two blocks B supporting the rail-section C and there are two blocks B supporting the rail-section C'. Thus when 60 the blocks are mounted on the base-plate A and the rail-sections C C' mounted on the blocks the rail-sections must aline. Adapted to rest upon the surface of the base A are blocks D. These blocks are flat on the under 65 side, the projection being dispensed with; but there is a rib d on the upper face of each block similar to the rib b' of the block B. This rib d fits the groove in the crossing rails F F'. The blocks being smooth on the under 70 side can be placed in any position on the base-plate A. In the present instance, as shown in Fig. 1, the rail-sections C and F are coupled together by bolts c c' and the rail-sections C' and F' are coupled together by 75 bolts c² c³, so that it will be seen that the rails C and F and C' and F' are secured together before the rails are placed on the base-plate A. Thus when the rails C and C' are properly 80 mounted on their blocks, which are adapted to grooves in the base-plate, the four rails must necessarily bear the proper relation to each other. The space between the end of the rail-sections in the present instance is intended to be filled in by a casting, which may form the 85 entire center of the frog structure. As shown by dotted lines, this casting may have a recess in its upper surface for the reception of a hard-metal plate. When the rail-sections are in proper position and supported by their 90 respective blocks B and D, they are firmly clamped to the base-plate by cross-bars E E and vertical bolts e, which pass through slots e' in the cross-bars E and through slots e² in the base-plate A. By making slots in the 95 base-plates and in the cross-bars the bolts can be adjusted as desired. There may be any number of slots in the plates, depending upon the character of the work to be clamped.

In Figs. 7, 8, and 9 I have shown a modifi- 100

cation of the device used particularly for clamping rail-sections to form switches and switch mates. In the base-plate A' (shown in Fig. 7) are two parallel grooves $a^3 a^4$, and in the base-plate are a series of slots e^3 for the reception of the securing-bolts. The same blocks B and D are used in connection with the base-plate A' as with the base-plate A, and the rail-sections are secured in position on these blocks, as indicated in the figures, the rail-sections C² and C³ being in line, while the section F² is secured to a section C³ on an angle by means of bolts $c^4 c^5$. After the rail-sections are in position, as shown, the mold is made in the sand, as in Fig. 9, and molten metal is cast within the space between the ends of the rail-sections forming the switch or mate casting. The mold is also formed so that the casting will bind the rail-sections firmly in position, so that other fastenings are not required.

I may use a plate having a single groove; but I prefer to make a plate having a series of grooves, as shown, so that standard frogs, switches, or mates can be readily made.

I claim as my invention—

1. The combination in means for securing rails together in the process of forming rail structures, of a base-plate having a longitudinal guide the parts of which are in alignment, and blocks engaging with said guide and shaped to engage with the rails clamped thereto and to hold the same in alignment with the blocks, substantially as described.
2. The combination of a base-plate having a groove the parts of which are in alignment therein, blocks, each block having a tongue adapted to the groove, and having a rib on its

upper face adapted to the groove in a rail-section, and a clamp for holding the said section to the blocks, substantially as described.

3. The combination in means for securing rails together, in the process of forming rail structures, of a base-plate having a guide the parts of which are in alignment, two sets of blocks, one set fitted to the guide and the other set adapted to rest upon the surface of the base-plate, and means for securing the rails to the base-plate, substantially as described.

4. The combination of a base-plate having a groove in its upper surface, two sets of blocks, one set of blocks having tongues on their under side adapted to grooves in the base-plate, the other set of blocks being smooth on the under side, each block having a rib adapted to the groove in the rail-sections, and means for clamping the rail-sections to the block and to the base-plate, substantially as described.

5. The combination of a base-plate having two or more grooves at an angle to each other, each of which grooves has its parts in alignment, two or more sets of blocks having tongues adapted to the grooves, ribs on the upper face of each block adapted to the grooves in the rail-sections, with means for securing the rail-sections to the blocks and to the base, substantially as described.

In testimony whereof I have signed my name to this specification in the presence of two subscribing witnesses.

ARTHUR B. DAVENPORT, JR.
